UNITED STATES PATENT OFFICE

JOHNSON CONRAD FALLS, OF ST. JOSEPH, LOUISIANA

SAW GUIDE

Application filed August 4, 1930. Serial No. 473,030.

The present invention relates to saw guide adapted particularly for use with circular saws and comprises principally a pair of guide jaws positioned at opposite sides of the saw at a point thereof remote from the work and arranged to prevent vibration of the saw during the rapid rotation thereof.

An important object of the invention is to provide a saw guide of this character in which adjustments may be made to the jaw ends of the guide without danger of injury to the workmen by coming into contact with the saw.

Another object is to provide means for adjusting the saw guide bodily in a direction transversely with respect to the saw blade and also to provide a swinging mounting for the guide whereby to permit the same to be moved into operative position with respect to saws located at opposite sides of the guide and further embodying means for securing the guide in either of its opposite positions in order to prevent accidental displacement thereof during the operation of the saw.

A still further object is to provide removable inserts for the jaw faces of the guides so that the same may be replaced when worn, due to constant frictional engagement with the sides of the rotating saw.

Another object is to provide a device of this character of a simple and practical construction, which may be installed in operative position upon a saw machine without necessitating any changes in the construction or operation thereof which is efficient and reliable in performance, relatively inexpensive to manufacture and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

Figure 1 is a top plan view of the guide in operative position with respect to the saw,

Figure 2 is a sectional view through the base along a line 2—2 of Figure 1,

Figure 3 is a longitudinal sectional view through the pivotal mounting for the guide taken along a line 3—3 of Figure 1, and

Figure 4 is a sectional view taken longitudinally of the pair of jaws forming the guide, substantially along a line 4—4 of Figure 1.

Referring now to the drawings in detail, for the purpose of illustration I have disclosed a preferred embodiment of my invention, which comprises a base member 5 adapted for attachment to the saw machine in any suitable manner in a position adjacent the saw 6.

The base 5 is formed intermediate its ends with a bearing support 7 in which is rotatably mounted a shaft 8, said shaft being also adapted for longitudinal movement with respect to the bearing. On one end of the shaft 7 is formed a substantially jaw shaped member 9, forming one of the elements of the guide, said jaw member being disposed at right angles with respect to the shaft and formed with a bifurcated section 10 intermediate its ends at a position in longitudinal alignment with the shaft.

Between the bifurcations 10 is fitted a reduced section 11 formed on the inner side of a second jaw member 12, said jaw members being secured for pivotal movement by a pin 13 extending through the bifurcated section 10 and reduced section 11.

The end of the shaft 8 opposite from the jaw member 9 is provided with a threaded bore 14 within which is threadedly inserted an adjusting screw 15 having its outer end formed into an operating knob or wheel 16. A collar 17 is fixedly secured upon the screw, outwardly from the shaft and in spaced relation from the knob 16.

The portion of the screw disposed between the knob 16 and the collar 17 is journaled for rotation in an opening formed in a bearing support 18, the collar 17 and the knob 16 preventing longitudinal movement of the screw and accordingly causing the longitudinal movement of the shaft 8 so as to provide for the transverse adjustment of the jaw members 9 and 12 with respect to the saw 6.

The shaft 8 is provided with a pair of longitudinally extending grooves 19 at diametrically opposite sides of the shaft, said grooves being adapted to receive the eccentric end 20 of a lever 21 pivotally mounted at one side of the bearing support 7 and disposed in a slotted opening formed in said bearing.

It will be apparent that the eccentric end 20 may engage the opposite grooves 19 upon a turning movement of the shaft a half turn, or one hundred and eighty degrees. Accordingly the jaw members 9 and 12 may be turned upon the shaft 8 so as to extend the jaw ends 22 thereof in opposite direction and thus may be disposed in saw guiding position with respect to saws positioned adjacent opposite ends of the base 5.

Supports 23 are carried at opposite ends of the base 5 upon which the jaw members may rest when disposed in their opposite positions. The jaw ends 22 of each of the jaw members 9 and 12 are disposed in slightly spaced apart relation as clearly illustrated in Figure 1 of the drawings and have their opposed faces formed with recesses within which are fitted inserts 24 projecting outwardly from the opposed faces of the jaws and arranged in slightly spaced relation from the opposite faces of the saw base.

At the opposite ends of the jaw members 9 and 12 is arranged an adjusting screw 25, the screw being threaded through the end of one of the jaw members and engaging the other of the jaw members and adapted to prevent the movement of the jaw ends 22 in a direction away from each other.

A leaf spring 26 is attached at one end to one of the jaw members by screws or the like 27 and with its opposite end arranged in engagement with the other of said jaw members for yieldably urging the members apart.

The ends of the jaws forming the guide are thus adjustably disposed at opposite sides of the saw base, at a point remote from the work so as to prevent vibration in the saw blade during the rapid rotation thereof.

It will be apparent that adjustments of the guide may be made with respect to the saw without the necessity of the hands of the workmen coming into contact with the saw and accordingly the guide may be properly adjusted during the operation of the saw.

It is obvious that my invention is susceptible to various changes and modifications in construction without departing from the spirit of the invention or the scope of the appended claim, and I accordingly claim all such forms of the device to which I am entitled.

Having thus described my invention, what I claim as new is:

A saw guide of the class described comprising a base having a bearing part thereon, a shaft rotatably and slidably arranged

in said bearing part, means at one end of the shaft for moving the same longitudinally, a stationary jaw having an intermediate part on one of its sides integrally connected to the other end of the shaft, a movable jaw pivoted intermediate its ends to the opposite side of said stationary jaw, saw engaging elements carried by the jaws at one end thereof, a set screw carried by the opposite end of the stationary jaw and engaging the adjacent end of the movable jaw, said shaft having longitudinally extending grooves therein arranged diametrically opposite each other, a lever hinged to one side of the bearing part and having a cam thereon for engaging either groove to hold the shaft in either one of its two positions and an angle shaped stop at each end of the base having one arm connected with the base and its other arm extending horizontally from the base into the path of movement of the stationary jaw for supporting the jaw in operative position.

In testimony whereof I affix my signature.

JOHNSON CONRAD FALLS.
